UNITED STATES PATENT OFFICE.

JOSEPH D. CARNEY, OF CHICAGO, ILLINOIS.

SIGN CHARACTER AND SECURING MEANS THEREFOR.

Application filed February 9, 1926. Serial No. 87,058.

This invention relates to novel means for securing sign characters, such as letters and numerals, to awnings, canvas tents and the canvas tops of vehicles, and has for one of its objects the provision of means of this character which shall be simple, durable and inexpensive and through the medium of which a skilled or unskilled person can readily secure the sign characters to the article to which they are to be applied.

A further object of the invention is the provision of means of the character stated which will permit the sign characters to be secured in place without noticeably distorting the article to which they are secured and which will permit the ready removal of the sign characters in order to secure them to another article or new ones substituted therefor.

A still further object of the invention is to secure the sign characters to the article in a manner to permit the free circulation of air between the parts whereby to prevent the accumulation of moisture between the sign characters and article and the consequent deterioration of the parts.

With the foregoing and other objects in view, the invention consists of the novel construction, combination and arrangement of parts hereinafter fully described and claimed, and illustrated in the accompanying drawing, wherein:

Figure 1 is an elevational view illustrating the application of a sign character embodying my invention,

Figure 2 is a similar view illustrating a part of the sign character securing means,

Figure 3 is a detail sectional view taken on the horizontal plane indicated by the line 3-3 of Figure 1,

Figure 4 is a detail sectional view taken on the vertical plane indicated by the line 4-4 of Figure 1,

Figure 5 is a sectional view of a slightly modified form of the sign character securing means, and

Figure 6 is a similar view of a further modified form of the sign character securing means.

Corresponding and like parts are referred to in the following description, and designated in the several views of the accompanying drawing, by similar reference characters.

In the drawing, 1 designates the sign character and 2 the article to which it is secured. The article 2 may be made of can-

vas or other flexible material and may consist of an awning, canvas tent, the canvas top of a vehicle or the like. The sign character 1 is provided in its inner side with a recess 3 which opens out through the upper and lower ends thereof and permits the free circulation of air between all parts of the sign character and the article 2 in order to prevent the accumulation of moisture between the parts and the consequent deterioration of the part 2. The sign character 1 may be made of metal, wood or other suitable material, and is provided in its front side with recesses 4 in the bottom walls of which openings 5 are provided.

The means for securing the sign character 1 to the article 2, comprises an internally threaded sleeve 6 provided at one end with an outer flange 7, a threaded stud 8 provided at one end with a head 9, and a backing or washer strip 10. The sleeve 6 passes through the article 2 and the inner end thereof contacts with the sign character 1. The stud 8 passes through the sign character 1 and is engaged with the sleeve 6, and the head 9 of the stud occupies a recess 4. The strip 10 is positioned between the flange 7 of the sleeve 6 and the article 2, and is provided with an opening 11 for the reception of the sleeve. The head 9 is of less thickness than the depth of the recess 4 so as to permit the recess to be closed in a manner to obscure the head from view by any suitable material, as indicated at 12. A nick 13 is formed in the head 9 to permit the stud 8 to be applied or removed by means of a screwdriver.

In practice, the sign character will be secured at one or more points to the article. The number of points at which the sign character is secured to the article will depend solely upon the size of the former. To adapt the article for the application of the sign character thereto, it is only necessary to provide the former with one or more openings for the reception of the sleeve or sleeves. As the sleeve 6 contacts with the inner side of the sign character 1 and the head 9 with the opposite side of the sign character, as the flange 7 contacts with the strip 10, and the latter forms a backing for the vertical edges of the sign character, it should be apparent that the sign character is firmly secured in place and that the article is not noticeably distorted. After the application of the sign character 1, the ma-

terial 12 can be applied. As the material hides the head 9, the securing means will not detract from the appearance of the sign character.

5 The securing means shown in Figure 5 differs from that shown in Figures 1, 2 and 3 in that a grommet 14 and nut 15 are used in place of the sleeve 6 and flange 7 and in that a stove bolt 16 is used in place of the 10 parts 8 and 9 which constitute a machine screw. The grommet 14 is secured to the article 2 and contacts with the inner or opposing sides of the sign character 1 and strip 10. The structure shown in Figure 15 6 differs from that shown in Figure 5 in that a washer 17 is used in place of the strip 10, the washer being positioned on the bolt 16 between the inner or opposing sides of the grommet 14 and sign character 1. The 20 sleeve 6 of the structure shown in Figures 1, 2 and 3, the grommet 14 of the structure shown in Figure 5, and the grommet 14 and washer 17 of the structure shown in Figure 6, prevent the inward distortion of the sign 25 character while securing it in place.

It should be understood that the drawing is merely illustrative and does not pretend to give exact proportions. Furthermore, the said drawing is illustrative of a 30 preferred construction, it being my expectation that various changes and modifications may be made without departing from the spirit and scope of my invention.

What is claimed is:—

35 1. In combination, a freely flexible article, a sign character having a recessed inner side and arranged with its edges in contact with the article, a bolt passing through the sign

character and article, a nut applied to the bolt, means mounted on the bolt between the article and the nut and extending from edge to edge of the sign character to engage the article against the edges of the sign character, and a member surrounding the bolt and extending from the nut to the inner side of the sign character and adapted in conjunction with said means to limit the distance that the nut may be turned up and thus prevent the noticeable distortion of the article.

2. In combination, a freely flexible article, a sign character having a recessed inner side and arranged with its edges in contact with the article, a bolt passing through the sign character and article, a nut applied to the bolt, a backing or washer strip mounted upon the bolt between the article and nut, and extending from edge to edge of the sign character and a member surrounding the bolt between the sign character and nut and adapted in conjunction with said strip to limit the distance that the nut may be turned up and thus prevent the noticeable distortion of the article.

3. In combination, a freely flexible article, a sign character having a recessed inner side and arranged with its edges in contact with the article, a bolt passing through the sign character and article, a nut applied to the bolt, and a backing or washer strip mounted upon the bolt between the article and nut and extending from edge to edge of the sign character and adapted to limit the distance that the nut may be turned up and thus prevent the noticeable distortion of the article.

In testimony whereof I affix my signature.
JOSEPH D. CARNEY.
